MICROBIOLOGICALLY ACTIVE QUATERNARY
AMMONIUM COMPOUNDS

Reginald L. Wakeman, Philadelphia, Pa., and Joseph F. Coates, Washington, D.C., assignors, by mesne assignments, to Millmaster Onyx Corporation, New York, N.Y., a corporation of New York
No Drawing. Filed Apr. 13, 1964, Ser. No. 359,501
13 Claims. (Cl. 260—501.15)

The present invention has for its object the preparation of relatively insoluble, microbiologically active compounds by reaction of certain quaternary ammonium hydroxides or their water-soluble salts with 4,4-bis(p-hydroxyphenyl)pentanoic acid and certain of its derivatives or their water-soluble salts.

The quaternary ammonium compounds used in the process of this invention contain at least one carbon chain having from 8 to 22 carbon atoms and also possess at least one benzyl radical attached to the quaternary nitrogen atom. The benzyl radical may, if desired, be substituted by alkyl groups or halogen atoms. The quaternary ammonium compounds, moreover, possess only non-heterocyclic nitrogen atoms. In general, the quaternary ammonium compounds used in the present invention comply with the formula:

where R' is an alkyl radical containing from 8 to 22 carbon atoms or an alkyl benzyl radical in which the benzyl group may contain a substituent methyl radical and in which the alkyl group contains 8 to 22 carbon atoms and R'' is a benzyl or substituted benzyl radical or a methyl group if R' is an alkyl benzyl radical containing eight or more carbon atoms in its alkyl substituent. X in the above formula is chlorine, bromine, iodine, sulfate, methosulfate, ethosulfate and the like.

Typical examples of these quaternary ammonium compounds are alkyl dimethyl benzyl ammonium chloride in which the alkyl group may have from 8 to 22 carbon atoms, alkyl dimethyl substituted benzyl ammonium chlorides in which the alkyl radical contains from 8 to 22 carbon atoms and in which the benzyl radical is substituted with one or more side chains containing from 1 to 5 carbon atoms such, for example, as methyl, dimethyl, trimethyl, tetramethyl, ethyl, diethyl, isopropyl, tertiary butyl and isoamyl or with one, two or more halogen atoms

such as chlorine and bromine, alkyl dimethyl menaphthyl ammonium chloride and alkyl dimethyl tetrahydro-menaphthyl ammonium chloride in which the alkyl radical contains from 8 to 22 carbon atoms, alkyl benzyl trimethyl ammonium chloride in which the alkyl radical contains from 8 to 22 carbon atoms and in which the aromatic nucleus of the benzyl radical may, if desired, be substituted by one or more methyl or other lower alkyl groups and mixtures of the aforesaid quaternary ammonium compounds.

In general, we prefer to use such quaternary ammonium compounds which have a phenol coefficient of at least 100 with respect to both *Staphylococcus aureus* and *Salmonella typhosa* at 20° C. when determined by the standard method given in the "Official Methods of An-

alysis of the Association of Official Agricultural Chemists," ninth edition (1960), page 63 at seq.

The 4,4-bis(p-hydroxyphenyl) pentanoic acid which is used in this invention is commercially available under the designation of "Di-Phenolic Acid" from S. C. Johnson and Son, Incorporated in Racine, Wis. and is described by them as produced by the condensation of phenol and levulinic acid. "Di-Phenolic Acid," as well as "DPA" hereinafter used, are registered trademarks of S. C. Johnson and Son, Incorporated. Derivatives such as 4,4-bis(nitro-hydroxyphenyl) pentanoic acid can be obtained similarly by the condensation of nitrophenol with levulinic acid and analogous compounds may also be prepared by substituting for nitrophenol, for example, halo-phenols and the like. Derivatives of 4,4-bis(p-hydroxyphenyl) pentanoic acid may also be obtained by reacting the phenolic hydroxy groups of that compound with such agents as carboxylic acids to yield phenolic ester groups or with alkyl halides to yield phenolic ether groups. Other derivatives may also be obtained by reacting the activated hydrogens in the 3 and 5 positions of one or both of the phenyl nuclei by halogenation, nitration, sulfonation and alkylation. Other derivatives may also be obtained by means of the Mannich reaction, wherein formaldehyde and ammonia or alkyl amines are employed to attach one or more amino groups in the 3 and 5 positions of one or both of the phenyl nuclei. Other derivatives may also be made by condensing two or more molecules of the 4,4-bis(p-hydroxyphenyl) pentanoic acid by reacting them with a suitable proportion of a dihaloalkane such as dichlorobutane or with dichloroethyl ether or with epichlorohydrin and the like to form polyether acids.

Typical of the derivatives of the 4,4-bis(p-hydroxyphenyl) pentanoic acid which may be used in this invention, in addition to the acid itself, are the mono- and dichloro, mono- and di-bromo, mono- and di-nitro, mono- and di-methyl, mono- and di-sulfonic acid, mono- and di-methyl-, ethyl-, propyl- or butyl- ether, mono- and di-formic, acetic or propionic ester, mono- or poly-amino-, methyl amino- or dimethyl amino- phenyl substituted compounds and the like. Also, we may use poly-ether acids containing on the average from two to five acid units joined with either bridges.

The quaternary ammonium salts of 4,4-bis(p-hydroxyphenyl) pentanoic acid, otherwise called "Di-Phenolic Acid," or for the sake of brevity DPA, and its derivatives embraced within the scope of this invention may be represented as follows:

wherein R may be $—(\text{CH}_2)_4—$ or
 $—(\text{CH}_2)_2—\text{O}—(\text{CH}_2)_2—$
 $—\text{CH}_2\text{—CHOH—CH}_2—$ and the like, and n is any number from zero to four on the average, and X¹, X₁, Y and Z may be hydrogen, a metal, an organic base and at least one of which is a quaternary ammonium cation, and one or more of the 3 or 3,5 positions of one or more of the benzene rings may be nitro, halo, alkyl or sulfonic acid substituted.

The compounds of this invention may be prepared by mixing aqueous solutions of the quaternary ammonium salts or hydroxides with an aqueous solution of the acid in question or any of its water-soluble salts. The ratio of quaternary ammonium compound to acid should be such

as to permit complete salt formation between the quaternary ammonium compound and all of the carboxylic groups, or the carboxylic and one or both of the phenolic groups if any, of the 4,4-bis(p-hydroxyphenyl) pentanoic acid or its derivatives. Thus, mono, di or tri quaternary ammonium salts may be formed.

In the case of the polyether acids, the carboxylic salts are normally considered, but the salts of the residual phenolic groups may also be included, if desired.

After thorough mixing, the organic product layer is separated from the aqueous layer (as with a separatory funnel) since two distinct phases are formed. Separation may be facilitated by the addition of an organic solvent immiscible with water. The product layer may be washed with water to remove any residual by-product salt or unreacted materials. The solvent, if any, may be evaporated and the product air or vacuum dried to a paste, wax, oil or solid.

It is not necessary to use an aqueous medium. Any solvent or solvent mixture in which the starting materials are soluble will be satisfactory. Non-aqueous solvents facilitate the separation of by-product inorganic salt and reduce the need for vacuum drying to get an anhydrous product. When a non-aqueous medium is employed, it is usually necessary to add a small amount of water to facilitate ionic reaction.

The product may be used, if desired, without drying since any entrapped water is irrelevant to the microbiological activity of the compounds. In other applications, removal of water may be essential for reasons not related to biological activity.

An alternative method for the preparation of compounds especially applicable to the treatment of fabric, ropes, net woven and non-woven fabric and reticulated or convoluted materials, involves a two-step process. In the first step, the material is passed through a bath containing the anionic moiety. Excess solution is removed by methods well known to those skilled in the art. The treated material is then passed through a second bath wherein the concentration of quaternary ammonium compound is such that the material pickup will result in an equivalent amount of quaternary ammonium compound reacting with the anionic moiety, depositing the product in the most intimate way on the surface and in the interstices, convolutions and reticulations of the material.

The method of adjustment of solution concentration to achieve the required pickup is well known to those skilled in the art. The order of treatment may be reversed without affecting the biological activity or durability of the product on the material. The products of this invention may be formulated as water dispersions by dissolving them in a water-miscible organic solvent such as acetone or methanol and diluting with water or by dissolving them in emulsifiable oils such, for example, as sulfonated castor oil or pine oil and diluting with water. In preparing aqueous dispersions, emulsifying agents such, for example, as ethylene oxide condensates of alkyl phenols may be used with or without organic solvents.

It is surprising that the compounds of this invention exhibit high microbiological activity despite their relative insolubility in water. Because of their unusual combination of physical and microbiological properties, they can be used to impart laundry-resistant anti-microbial characteristics to textiles. They can also be used as the active agent in antimildew finishes for textiles which are resistant to leaching with water.

Although the compounds have low water solubility, they are compatible with various organic solvents, plasticizers and high molecular weight compounds. Consequently, they may be incorporated as anti-microbial agents in synthetic resins and plastics. The compounds are compatible with natural and synthetic rubber latices. Therefore, they may be used to prepare bacteriostatic films and molded objects deposited from such latices.

The compounds can be incorporated into cutting and grinding fluids without precipitation. Also, they blend well with non-ionic and anionic surface active agents. In such compositions they retain their microbiological activity.

It will be understood that the properties of the products described herein will vary depending upon the nature of the quaternary ammonium compound used in their preparation as well as the aromatic carboxylic acid or salt reacted therewith.

The chemical, physical and biological properties of the products of our invention make them especially appropriate for the following applications when suitably incorporated in active amounts in an appropriate vehicle, binder, medium or substrate:

- (1) Mildewproofing fabric, canvas, ropes, textiles, awnings, sails, tenting and other woven and non-woven reticulated materials.
- 20 (2) Paint mildewstats.
- (3) Jet plane fuel additive to control growth of micro-organisms.
- (4) Odor preservative agents for clothes and shoes.
- (5) Mildew retardant and odor suppressant for shoes and other leather products.
- 25 (6) Topical antiseptics.
- (7) Antidandruff agents.
- (8) Disinfection agents for hair and gut of man and beast.
- 30 (9) Bacteriostatic furniture dressing.
- (10) Surface finishes for stone, plaster, tile, cement, brick and other inorganic building materials, to retard growth of microorganisms, fungi, mold and algae.
- (11) Wool preservative.
- 35 (12) Plant and tree spray to combat fungi.
- (13) Antimycotic agents for soap wrappers.
- (14) Self-sanitizing brushes.
- (15) Mildewproofing agent in and on plastic and film.
- (16) Mildewproofing of cellulosics, cardboard, fibre-board, paper and cordage.
- 40 (17) Contact biostat for application to film, waxes and cloth to preserve cheese, meats and vegetables and other food products.
- (18) Algal inhibition, especially on surfaces and in solution where low foaming is desirable.
- 45 (19) Paper pulp slime control.
- (20) Sanitizing agent for rug, carpet, curtains.
- (21) Egg preservation.
- (22) Adhesive preservation.
- 50 (23) Preservation of latex paints.
- (24) Preservation of metal-working compounds.
- (25) Additives for soap and for both anionic and non-ionic detergents in liquid, bar, powder, bead, solution and other forms to impart bacteriostatic and fungistatic properties thereto.

The microbiological activity of our compounds has been evaluated for microbiological stasis by the Standard Tube Dilution Test, the technique for which is common knowledge to those skilled in the art. A Difco Bacto CSMA Broth #0826 was used in the study. This test is used to determine the lowest concentration of microbiologically active compounds which will inhibit the growth of the organism in question. For a wide range of applications, the inhibition of growth rather than outright kill is satisfactory.

Briefly put, the Tube Dilution Test consists in placing 9 cc. of the CSMA Broth in a test tube which is then sterilized in an autoclave. One cc. solution of the microbiologically active compound at an appropriate concentration is added to the test tube which is then inoculated with 0.1 cc. of a twenty-four hour old culture of the organism under study. The test tube is then incubated at 37° C. for forty-eight hours and observed for bacterial growth.

The same procedure is followed for fungi. In such tests, however, the tubes are incubated for fourteen days at a temperature suitable for optimum fungal growth, usually 25° C.

The invention is illustrated by, but not restricted to, the following examples:

EXAMPLE I

A stock solution was prepared in 10% concentration of the monosodium salt of 4,4-bis(p-hydroxyphenyl) pentanoic acid. Sixty ml. of this solution containing 0.0195 chemical equivalent weights of the compound was agitated vigorously while adding 80 ml. of an 11% solution of a commercial grade of alkyl dimethyl ethyl-benzyl ammonium chloride (Onyx Chemical Corporation's "BTC-471" in which the alkyl distribution is 50% C₁₂, 30% C₁₄, 17% C₁₆, 3% C₁₈). The agitated mixture was transferred to a separatory funnel where two phases separated. The organic product layer was removed and vacuum dried to yield a brown paste in 90% of theoretical yield of alkyl dimethyl ethyl-benzyl ammonium bis(p-hydroxyphenyl) pentanoate.

EXAMPLE II

The stock solution of monosodium salt of 4,4-bis(p-hydroxyphenyl) pentanoic acid of Example I was reacted in the same manner with a chemically equivalent amount of a solution of a commercial grade of alkyl dimethyl benzyl ammonium chloride (Onyx Chemical Corporation's "BTC-824" in which the alkyl distribution is 60% C₁₄, 30% C₁₆, 5% C₁₂, 5% C₁₈). The vacuum dried product was a brown paste in 100% of the theoretical yield of alkyl dimethyl benzyl ammonium bis(p-hydroxyphenyl) pentanoate.

EXAMPLE III

A 10% stock solution of the disodium salt of 4,4-bis(p-hydroxyphenyl) pentanoate was prepared. An aliquot of this solution containing 0.0182 molecular weights was agitated vigorously and two chemically equivalent weights of the solution of the alkyl dimethyl ethyl-benzyl ammonium chloride of Example I was added. On separating and vacuum drying the organic product layer, a brown paste was obtained in 50% of the theoretical yield of the di(alkyl dimethyl ethyl-benzyl ammonium) salt of bis(p-hydroxyphenyl) pentanoic acid.

EXAMPLE IV

In a similar manner, 60 ml. of the stock solution of the disodium salt of 4,4-bis(p-hydroxyphenyl) pentanoic acid of Example III was reacted with two chemically equivalent weights of the solution of the alkyl dimethyl benzyl ammonium chloride of Example II. The recovered and vacuum dried product was a brown paste in 62% of the theoretical yield of the di(alkyl dimethyl benzyl ammonium) salt of bis(p-hydroxyphenyl) pentanoic acid.

EXAMPLE V

A solution was prepared in 10% concentration of the trisodium salt of 4,4-bis(p-hydroxyphenyl) pentanoic acid. An aliquot of this solution containing 0.0170 molecular weights was reacted with three chemically equivalent weights of a solution of the alkyl dimethyl ethyl-benzyl ammonium chloride of Example I while agitating vigorously. The mixture was transferred to a separatory funnel and allowed to separate into two phases. The organic product layer was removed and vacuum dried. The resulting brown paste was recovered in 44% of the theoretical yield of tri(alkyl dimethyl ethyl-benzyl ammonium) salt of bis(p-hydroxyphenyl) pentanoic acid.

EXAMPLE VI

A solution of the monosodium salt of 4,4-bis(3-nitro-4-hydroxyphenyl) pentanoic acid was prepared in 5% concentration. An aliquot of this solution containing 0.00753 molecular weights of the compound was agitated vigorous-

ly while a chemically equivalent amount of the solution of alkyl dimethyl ethyl-benzyl ammonium chloride of Example I was added. The mixture was transferred to a separatory funnel along with a small amount of benzene to facilitate phase separation. The organic product layer was removed and vacuum dried. A red paste was obtained in 98% of the theoretical yield of alkyl dimethyl ethyl-benzyl ammonium bis(3-nitro-4-hydroxyphenyl) pentanoate.

EXAMPLE VII

10 A polyether acid was prepared by reacting 4,4-bis(p-hydroxyphenyl) pentanoic acid and dichloroethyl ether in such proportions that on the average there were approximately four carboxylic acid groups in the molecule. It was found to have an acid number of 156.7 and therefore a combining weight of 358.

15 A 10% stock solution of the sodium salt of this compound was prepared in water. An aliquot containing 0.0158 chemical equivalents was agitated vigorously and a chemically equivalent amount of a solution of the alkyl dimethyl ethyl-benzyl ammonium chloride of Example I was added. The mixture was poured into a separatory funnel and allowed to separate into two phases. The organic product layer was vacuum dried to yield a brown paste in the theoretical yield of poly(alkyl dimethyl ethyl-benzyl ammonium) salt of the said polyether acid.

20 In a similar manner, by using the alkyl dimethyl benzyl ammonium chloride and the technique of Example III, the poly(alkyl dimethyl benzyl ammonium) salt of the polyether acid was obtained in theoretical yield.

EXAMPLE VIII

25 A polyether acid was prepared by reacting 4,4-bis(p-hydroxyphenyl) pentanoic acid and epichlorohydrin in such proportions that there were approximately four carboxylic acid groups in the molecule. It was found to have an acid number of 155 and therefore a combining weight of 362.

30 A 10% stock solution of the sodium salt of this compound was prepared in water. An aliquot of this solution containing 0.0339 chemical equivalents was agitated vigorously while adding a solution of the alkyl dimethyl ethyl-benzyl ammonium chloride of Example I, in chemically equivalent amount. The mixture was separated into two phases in a separatory funnel and the organic product layer was removed and vacuum dried. A brown solid was obtained in 93% of the theoretical yield of the poly(alkyl dimethyl ethyl-benzyl ammonium) salt of the said polyether acid.

35 In a similar manner, by substituting the alkyl dimethyl benzyl ammonium chloride of Example II for the alkyl dimethyl ethyl-benzyl ammonium chloride of Example I, the poly(alkyl dimethyl benzyl ammonium) salt of the said polyether acid was obtained in 100% of the theoretical yield.

EXAMPLE IX

40 A polyether acid was prepared by reacting 4,4-bis(p-hydroxyphenyl) pentanoic acid with 1,4-dichloro butane in such proportions that on the average there were approximately five carboxylic acid groups in the molecule. It was found to have an acid number of 137 and therefore a combining weight of 410.

45 A 10% stock solution of the sodium salt of this compound was prepared. An aliquot of the solution containing 0.0231 chemical equivalents was agitated vigorously and a chemically equivalent amount of a solution of the alkyl dimethyl ethyl-benzyl ammonium chloride of Example I was added. The mixture was transferred to a separatory funnel, wherein two phases separated. The organic product layer was removed and vacuum dried. A brown solid product of poly(alkyl dimethyl ethyl-benzyl ammonium) salt of the said polyether acid was obtained in theoretical yield.

50 In a similar manner, using the alkyl dimethyl benzyl ammonium chloride of Example II, the poly(alkyl di-

methyl benzyl ammonium) salt of the said polyether acid was obtained in 100% of theoretical yield as a brown solid.

EXAMPLE X

The microbiological activity of the products of this invention is illustrated in Table I which shows the results obtained by means of the Standard Tube Dilution Test described above. The performance of the products listed in this table was determined with respect to *Staphylococcus aureus* (S.a.), *Salmonella typhosa* (S.t.) and *Aspergillus niger* (A.n.).

Table I

4,4-bis(p-hydroxyphenyl) pentanoic acid is designated below as "DPA" for the sake of brevity. The polyether acid obtained by reacting four mols of DPA with three of dichloro ethyl ether is designated as "4 DPA-3 E;" the polyether acid from four mols of DPA with three of epichlorohydrin as "4 DPA-3 G."

Quaternary	Acid	Reciprocal of Static Dilution of Product vs.—		
		S.a.	S.t.	A.n.
Alkyl Dimethyl	DPA, Mono Salt	10 ⁷	10 ⁵	10 ³
Ethyl-Benzyl	DPA, Di Salt	10 ⁷	10 ⁶	10 ⁴
Ammonium	DPA, Tri Salt	10 ⁵	10 ⁵	10 ⁵
Chloride	Dinitro-DPA	10 ⁷	10 ⁶	>10 ⁶
	4 DPA-3 E	10 ⁵	10 ⁵	10 ³
	4 DPA-3 G	10 ⁶	10 ⁵	10 ⁵
Alkyl Dimethyl	DPA, Mono Salt	10 ⁵	10 ⁶	10 ⁴
Benzyl	DPA, Di Salt	10 ⁶	10 ⁵	10 ⁴
Ammonium	DPA, Tri Salt	10 ⁶	10 ⁵	10 ⁵
Chloride	4 DPA-3 E	10 ⁶	10 ⁵	10 ³
	4 DPA-3 G	10 ⁶	10 ⁵	10 ⁴

We claim:

1. A quaternary ammonium salt of 4,4-bis(p-hydroxyphenyl) pentanoic acid and its derivatives having the formula:

wherein at least one of the 3 and 5 positions of at least one of the benzene rings in the formula is satisfied by a member selected from the group consisting of hydrogen, nitro, halo, lower alkyl and sulfonic acid radicals, and wherein R is selected from the group consisting of

—(CH₂)₄—(CH₂)₂—O—(CH₂)—,

and —CH₂—CHOH·CH₂—; n is any number from zero to an average of four; and X', X₁, Y and Z are each selected from the group consisting of hydrogen, an alkali metal and a non-heterocyclic quaternary ammonium cation having the structure:

wherein R' is an alkyl of 8 to 22 carbon atoms, R'' is a member of the group consisting of benzyl and substituted benzyl wherein the substituent is a member of the group consisting of alkyl having 1 to 5 carbon atoms, chlorine and bromine, said quaternary ammonium cation being at least one of said X', X₁, Y and Z.

2. Alkyl dimethyl ethyl-benzyl ammonium 4,4-bis(p-hydroxy phenyl) pentanoate, wherein the alkyl has from 12 to 18 carbon atoms.

3. Alkyl dimethyl benzyl ammonium 4,4-bis(p-hydroxyphenyl) pentanoate, wherein the alkyl has from 12 to 18 carbon atoms.

4. Di(alkyl dimethyl ethyl-benzyl ammonium) 4,4-bis(p-hydroxyphenyl) pentanoate, wherein the alkyl has from 12 to 18 carbon atoms.

10 5. Di(alkyl dimethyl benzyl ammonium) 4,4-bis(p-hydroxyphenyl) pentanoate, wherein the alkyl has from 12 to 18 carbon atoms.

6. Tri(alkyl dimethyl ethyl-benzyl ammonium) 4,4-bis(p-hydroxyphenyl) pentanoate, wherein the alkyl has from 12 to 18 carbon atoms.

15 7. Alkyl dimethyl ethyl-benzyl ammonium 4,4-bis(3-nitro-4-hydroxyphenyl) pentanoate, wherein the alkyl has from 12 to 18 carbon atoms.

8. Poly(alkyl dimethyl ethyl-benzyl ammonium) salt of the polyether acid reaction product of 4,4-bis(p-hydroxyphenyl) pentanoic acid and dichloroethyl ether and having on the average about four carboxylic acid groups in the molecule, wherein the alkyl has from 12 to 18 carbon atoms.

20 9. Poly(alkyl dimethyl benzyl ammonium) salt of the polyether acid reaction product of 4,4-bis(p-hydroxyphenyl) pentanoic acid and dichloroethyl ether and having on the average about four carboxylic acid groups in the molecule, wherein the alkyl has from 12 to 18 carbon atoms.

30 10. Poly(alkyl dimethyl ethyl-benzyl ammonium) salt of the polyether acid reaction product of 4,4-bis(p-hydroxyphenyl) pentanoic acid and epichlorohydrin and containing about four carboxylic acid groups in the molecule, wherein the alkyl has from 12 to 18 carbon atoms.

35 11. Poly(alkyl dimethyl benzyl ammonium) salt of the polyether acid reaction product of 4,4-bis(p-hydroxyphenyl) pentanoic acid and epichlorohydrin and containing about four carboxylic acid groups in the molecule, wherein the alkyl has from 12 to 18 carbon atoms.

40 12. Poly(alkyl dimethyl ethyl-benzyl ammonium) salt of the polyether acid reaction product of 4,4-bis(p-hydroxyphenyl) pentanoic acid and 1,4-dichloro butane and having about five carboxylic acid groups in the molecule, wherein the alkyl has from 12 to 18 carbon atoms.

45 13. Poly(alkyl dimethyl benzyl ammonium) salt of the polyether acid reaction product of 4,4-bis(p-hydroxyphenyl) pentanoic acid and 1,4-dichloro butane and having about five carboxylic acid groups in the molecule, wherein the alkyl has from 12 to 18 carbon atoms.
